Inventor:

UNITED STATES PATENT OFFICE.

JOHN B. BAXTER, OF WATERVLIET, NEW YORK, ASSIGNOR TO COVERT MANUFACTURING COMPANY, OF WATERVLIET, NEW YORK, A CORPORATION OF NEW YORK.

COMBINED BREAST-STRAP SLIDE AND ATTACHING MEANS THEREFOR.

1,227,871.

Specification of Letters Patent.

Patented May 29, 1917.

Application filed December 12, 1916. Serial No. 136,564.

To all whom it may concern:

Be it known that I, JOHN B. BAXTER, a citizen of the United States, residing at Watervliet, in the county of Albany and 5 State of New York, have invented certain new and useful Improvements in Combined Breast-Strap Slides and Attaching Means Therefor, of which the following is a specification, reference being had therein to the 10 accompanying drawing.

This invention relates to combined breast strap slides and attaching means therefor.

In my copending application filed concurrently herewith, I have illustrated and 15 described a novel and improved combination article of the character just referred to, which includes a breast strap slide proper and a pivotally connected snap hook or the like, and having among its objects increased 20 strength and durability, and to overcome to an appreciable extent the usual incident wear upon the edges of the strap in the movement of the latter relative to the slide.

It is one of the objects of the present invention to incorporate in a device of the 25 general character illustrated and described in my copending application, means whereby to further reduce the friction in the movement of the strap, thereby facilitating 30 the operation and increasing the life of the strap.

In carrying out the invention it is proposed to interpose in the body part of the breast strap slide, a roller or anti-friction 35 bearing for the strap, with the incident ease in operation of the latter, the other associated parts of the device being constructed and arranged to prevent undue wear upon the sides of the strap in the free movement of 40 the latter on the roller.

Another feature of the invention resides in a novel construction of slide having a strap engaging anti-friction bearing, of means for pivotally supporting the hook or 45 other attaching device to the slide, whereby in the relative swinging movement of the hook and slide, the slide will constitute a guide and reinforcement for the hook, and means for preventing lateral play of the 50 hook and undue strains upon the hook and pivotal supporting means therefor.

More particularly, the invention includes in combination with a breast strap slide having a strap engaging roller bearing, of

a hook or other supporting medium having 55 separated arm extensions pivotally mounted upon the body part of the slide whereby to constitute end abutments for the roller and edge abutments for the strap, the various parts of the device being constructed 60 and arranged with a view to neatness, simplicity, ease in operation, increased strength, and durability.

Other and further improvements and novel details in the construction and arrangement of the various parts of the device will be readily appreciated from the description to follow and from an inspection of the accompanying drawings, which form a part hereof, and wherein is disclosed 70 for the purpose of illustration a convenient embodiment of the invention, which has proven highly satisfactory in use.

In the drawings:—

Figure 1 is a perspective view of the combination device.

Fig. 2 is a top plan view of the breast strap slide and the parts positioned thereon.

Fig. 3 is a similar view of the breast strap slide with the associated parts removed.

Fig. 4 is a longitudinal sectional view of the slide and engaging end of the attaching device.

Fig. 5 is a transverse section, parts being broken away.

Referring to the drawings in detail, it will be noted that like reference numerals refer to corresponding parts throughout the several views, in which 1 designates opposed sides of the body portion of the breast strap 90 slide proper, said sides connecting with curved portions 2 separated from one another by a roller receiving space 3. Integral with the curved bottom portions 2 and the sides 1 of the slide are end loop members 95 comprising end bars 4 and side bars 5. The sides 1 of the body portion of the breast strap slide, as well as the bottom portions 2 thereof, project outwardly beyond the sides 5 of the loop extensions, and in said extended portions of said parts there is provided an elongated slot or recess 6.

Adapted to be pivotally mounted upon the breast strap slide as just described is a suitable hook or other attaching means. In the 105 illustrative embodiment of the invention, this attaching means takes the form of a snap hook comprising a hook portion 7, a

shank 8 having rearwardly projecting separated side arms 9, and a spring held pivotally mounted tongue 10, the opposite sides of which latter are adapted to engage over opposite sides of the shank 8, and the bill of the hook having suitable terminal lips or flanges overlying, and constituting guards for, the end of said tongue. The side arms 9 of the attaching device have rounded enlarged terminals 10 apertured at 11, whereas the sides 1 of the body portion of the breast strap slide have similar apertures 12. A suitable roller bearing 13 is adapted to be positioned in the space 3 of the breast strap slide, and conveniently a common means of support for the hook and roller is provided, the same in the embodiment of the invention illustrated, taking the form of a rivet or bolt 14 having headed ends to engage the outer surface of the sides 1 of the breast strap slide and loosely projecting through the apertures 11 of the hook arms 9 and through a central aperture extending through the roller 13. It will be observed that the engaging ends 10 of the hook arms 9 are positioned in the slotted portions 6 adjacent the sides of the body portion of the breast strap slide, and that the swinging movement of the hook is limited by the terminal walls of said slots which walls project beyond the edges of the curved portions 2, whereby to provide abutting shoulders to engage the inner surface of the arms 9 of the hook, when the hook has been moved to its limit in either direction.

The opposite arms 9 of the hook when in position on the breast strap slide constitute end abutments for the roller 13, and the arms 9 will be backed up by, and therefore reinforced on opposite sides by the roller and the sides 1 of the body portion of the slide.

It will also be observed that because of the positioning of the arms 9 in the slots 6 in the lateral extensions of the body part, the arms 9 will be in substantial alinement with the side arms of the loops 5, whereby the strap will be effectively guided at its edges by the side arms 5 of the loop members and the side arms 9 of the hook, and without any appreciable wear or friction, and in this connection it will be noted that the arms 4 and 5 of the upwardly curved looped portions are relatively wide and inclined as illustrated whereby to provide extended bearing surfaces for the strap.

In operation, the breast strap, conveniently of substantially the same width as the roller, is adapted to be inserted through the loop portions with the upper surface of the strap in contact with the under surface of the curved portions 2 of the slide and the under surface of the roller, whereas the pivotally mounted snap hook is adapted to detachably engage the neck yoke eye or other portion of the harness. The strap will

freely move on or over the roller, while its edges are guided by the sides 5 of the loop and the inner surfaces of the arms 9 of the hook. At the same time, the hook may readily move about its pivotal support over the inner surface of the sides 1 of the body portion of the slide, and undue strains on the arms 9, supporting rivet 14 and the like are overcome. When the hook has reached its limit of movement in either direction, the arms 9 fit in the terminal portions of the slots 6 and any unnecessary lateral strains in either direction of said arms is resisted by the shoulder portion 6^a on the one side and the sides 1 on the opposite side. 80

What I claim is:—

1. In a device of the character described, the combination of a breast strap slide having curved bottom portions separated from one another by a roller receiving space and having connecting sides, of an attaching member having opposed arms projecting into said space, a roller arranged between said arms in said space, and a pivotal supporting bearing projecting between the sides 90 of the slide for said roller and said arms. 85

2. In a device of the character described, the combination of a breast strap slide having a bottom portion and sides and terminal loop parts, said bottom portion having a 95 roller receiving recess and connecting side recesses, and an attaching device having side arms positioned in said side recesses, a roller positioned in said roller receiving recess, and means for pivotally supporting said side arms and loosely mounting said roller including a member projecting between the sides of the slide and through said roller and side arms. 100

3. In a device of the character described, the combination of a breast strap slide having a bottom portion and sides and terminal loop parts, said bottom portion having a roller receiving recess and connecting side recesses, and an attaching device having 110 side arms positioned in said side recesses, a roller positioned in said roller receiving recess, and means for pivotally supporting said side arms and loosely mounting said roller including a member projecting between the sides of the slide and through said roller and side arms, the sides of the loop members extending substantially parallel with the side arms. 115

4. In a device of the character described, 120 the combination of a breast strap slide having a curved body part with a roller receiving space and side recesses projecting beyond the opposite walls of said space, and a hook having rear side arm extensions positioned in said side recesses; means for pivotally mounting said arms whereby the same are free to move over the inner surface of the sides of the body part, and a loosely mounted roller positioned in the roller space 125 130

between said arm extensions whereby the latter constitute end abutments for the roller.

5. In a device of the character described, the combination of a breast strap slide comprising a curved bottom portion and side flanges, the bottom portion having an elongated roller receiving recess connecting with side recesses extending laterally beyond the 10 sides of the roller recess, said body portion having terminal loop members, a roller positioned in the roller space, and a hook having side arm extensions positioned in the side recesses of the body member and constituting end abutments for the roller, the 15 side arm extensions of the hook being separated from one another a distance substantially equal to the distance between the side arms of the loop members of the slide, and 20 a supporting pintle projecting between

the sides of the slide and loosely passing through the side arms of the hook and said roller.

6. In a device of the character described, the combination of a breast strap slide having 25 a curved body part and side flanges, a snap hook having side arm extensions mounted upon said flanges and overlying the inner surfaces thereof, and a roller for the strap supported on the slide at a point 30 between said arms whereby said arms constitute end abutments for the roller and guides for opposite edges of the strap.

In testimony whereof I hereunto affix my signature in the presence of two witnesses. 35

JOHN B. BAXTER.
